(57) **CLAIM**

The ornamental design for an electrolytic generator, as shown and described.

DESCRIPTION

1.1 is a top plan view of a first embodiment of an electrolytic generator;

1.2 is a bottom plan view thereof;

1.3 is a rear elevation view thereof;

1.4 is a front elevation view thereof;

1.5 is a right side elevation view thereof;

1.6 is a left side elevation view thereof;

2.1 is a bottom plan view of a second embodiment of an electrolytic generator;

2.2 is a top plan view thereof;

2.3 is a rear elevation view thereof;

2.4 is a left elevation view thereof.

2.5 is a front elevation view thereof;

2.6 is a top, front and left side perspective view thereof;

2.7 is a top, front and right side perspective view thereof.

The broken lines are shown for the purpose of illustrating parts of the article that form no part of the claimed design.

1 Claim, 13 Drawing Sheets(56)
